UNITED STATES PATENT OFFICE

WALTER P. MURPHY, OF CHICAGO, ILLINOIS, ASSIGNOR TO UNION METAL PRODUCTS COMPANY, OF CHICAGO, ILLINOIS, A CORPORATION OF DELAWARE

RAILWAY CAR CONSTRUCTION

Original application filed January 14, 1929, Serial No. 332,326. Divided and this application filed September 2, 1930. Serial No. 479,136.

The device relates to railway freight cars, particularly, to that class of equipment having doors which are opened or "dropped" to discharge part or all of the lading.

5 The object of the invention is to provide a spreader or beam for simultaneous operation of a pair of swingable doors in a railway freight car, which spreader is operated by any of the numerous door raising mechanisms now being marketed. A further object of the invention is to provide such a spreader or beam with spaced apart portions, each of which engages one of the swingable doors so as to permit the door to adjust itself 10 to the frame of the door opening about a substantially vertical and/or substantially horizontal axis, or in fact about any axis or axes, substantially parallel to the plane of the body part of the door, or by a combination 15 of movements, which may be termed a universal movement; furthermore, the door may move relative to the door in a plane substantially parallel to the body of the door. Any force applied to the operating mechanism adjacent the middle of the spreader is substantially equally distributed to the two doors, and furthermore, the force transmitted to one of the doors by the spreader is substantially equally distributed to the opposite vertical edges or margins of the door. In my construction, if the operating mechanism closes one door first, the operating mechanism continues functioning until the other door is closed; furthermore, if one side 20 of one door reaches closed position first, the operating mechanism continues to operate until the other side of such door reaches closed position; in fact, the mechanism operates until all four edges of the two doors 25 reach closed position.

A further object of the invention is to reduce the cost and weight of the spreader and car by forming it of a casting so that the metal can be evenly distributed commensurate with the stresses.

Another object of the invention is to engage the spreader with the door adjacent a stiffening rib or ribs so that the stresses caused by the lifting of the door will not be taken by the body portion of the door.

In the drawings:

Fig. 1 shows a typical application of my invention to a railway car.

Figs. 2 to 9 inclusive show various modified forms of the invention described herein.

Fig. 10 shows a partial side elevation of a car.

Fig. 1 shows a typical application of my invention to a typical so-called "hopper car" wherein the lower portion of the car on each side of the center sills 2 or center ridge is formed into a hopper, each hopper being provided with a swingable door 3. These doors are connected for simultaneous operation by a spreader 4 operated by a mechanism connected to the middle portion thereof and positioned between the center sills and under the ridge for protection from the lading and provided with a shaft extending to opposite sides of the car for operation by a wheel or wrench. There are numerous types of hopper dump cars in service on the railways with the hopper so positioned as to discharge the load between the rails and some designed to discharge the load outside of the rails. There are also dump cars used in the coke service having a floor sloping toward one side of the car with the side wall comprising a plurality of swingable doors to discharge the coke all on one side of the car. My invention is adaptable to any one of the above described cars, or in fact, to any car having two or more doors simultaneously closed by a single operative mechanism.

In Figs. 2 and 3 each end of the spreader is formed of U-shaped construction 48 and overlaps the reinforcing central web 49 of the door and is secured thereto by the bolt 50. The inner portion 51 and side portions 52 of the terminal U construction of the spreader are preferably formed on arcs so that the door may rock vertically and/or horizontally upon the spreader or vice versa.

Figs. 4 to 7 inclusive show a construction wherein the spreader 55 is connected to each door. The spreader and the doors may be provided with semi-spherical engaging surfaces 56-57 so that the door is free to slide upon the spreader to accommodate the inequalities of the car. The door is provided

with lips 58 which overlies a portion 59 of the spreader so that after the spreader is engaged with the two doors and the two doors are hinged to the car the spreader cannot 5 become disengaged from either of the doors until the hinge pins of one of the doors are removed.

Figs. 8, 9 and 10 show a construction wherein the doors and the spreader 62 are 10 provided with semi-spherical engaging surfaces 63—64 so as to permit universal movement between the spreader and each of the doors. The spreader in the form illustrated 15 is provided with a mushroom projection 65 and the doors are provided with flanges or lips 66 which engage the underside of the mushroom projection, but the lips only extend for part of the circumference of the semi-spherical bearing surface on the door and 20 portions of the head of the mushroom are cut away so that the door is connected to the spreader by inserting the mushroom under the lips and then revolving the door a few degrees, after which the doors are assembled 25 on the car and the hinge pins put in place. In this construction the spreader cannot become disengaged from either of the doors until the hinge pins of one of the doors have been removed. In this construction the door 30 may move relative to the spreader in a plane substantially parallel to the body portion of the door; also about an axis normal to the body portion of the door, which movement to permits the spreaders to adjust themselves to 35 the doors without any binding as the doors adjust themselves to the frames of the door openings.

In some cars the spreaders are extended to engage locking mechanisms supported by and 40 secured to the side of the car. A common form of locking mechanism comprises a hook 70 which falls into place by gravity and engages the extremities 71 of the spreader, which hook is held in place by a locking cam 72. In 45 some cars these outside locking mechanisms constitute the only means of holding the spreader and the doors in closed position. When it is desired to use such a locking mechanism I extend my spreaders so that their 50 extremities may engage such locking mechanisms.

The accompanying drawings illustrate the preferred form of the invention, though it is to be understood that the invention is not 55 limited to the exact details of construction shown and described, as it is obvious that various modifications thereof, within the scope of the claims, will occur to persons skilled in the art.

60 This is a division of my co-pending application Serial No. 332,326, filed January 14, 1929.

I claim:

1. In a railway car, a pair of hinged dumping doors, an equalizing spreader having

spaced apart portions, each engaging one of said doors adjacent its vertical medial line so as to permit universal movement between the door and the spreader, means to retain the spreader in operative relation to the door, 70 and a door operating mechanism attached to said spreader adjacent the center thereof.

2. In a railway car, a pair of hinged dumping doors and a spreader having spaced apart portions, each connected to one of said doors 75 so as to permit universal movement between the door and the spreader.

3. In a railway car, a pair of hinged dumping doors, each provided with a semi-spherical bearing, and a spreader having spaced apart semi-spherical journals engaging said bearing so as to permit universal movement 80 between the door and the spreader.

4. In a railway car, a pair of hinged dumping doors, each having a body part provided with a reinforcing web, a spreader having spaced apart U-shaped portions, each straddling the reinforcing web of one of said doors, the inner and side engaging surfaces 85 of said portions being formed on arcs so that the door may rock vertically and/or horizontally upon the spreader, and means to retain the portions in operative engagement with the web. 90

5. In a railway car, a pair of hinged dumping doors, each having a body part provided with a reinforcing web, and a spreader having spaced apart U-shaped portions, each straddling the reinforcing web of one of said doors and pivotally secured thereto, the inner 95 and side engaging surfaces of said portions being formed on arcs so that the door may rock vertically and/or horizontally upon the spreader. 100

6. In a railway car, a pair of hinged dumping doors and a spreader having spaced apart portions, each connected to one of said doors so as to permit movement between the door and the spreader about any one of several axes substantially parallel to the plane of the 105 body part of the door. 110

7. In a railway car, a pair of hinged dumping doors, each provided with a pintle having a semi-spherical bearing, and a spreader having spaced apart semi-spherical journals 115 engaging said bearings so as to permit movement between the door and the spreader about any one of several axes substantially parallel to the plane of the body part of the door.

8. In a railway car, a pair of hinged dumping doors, and a spreader having spaced apart portions, each connected to one of said doors so as to permit movement between the door and the spreader about any one of several axes substantially parallel to the plane of the body part of the door and also in a plane substantially normal to the plane of the body part of the door. 120

9. In a railway car, a pair of hinged 125

dumping doors, each provided with a pintle having a semi-spherical bearing, and a spreader having spaced apart semi-spherical journals engaging said bearings, each connected to one of said doors so as to permit movement between the door and the spreader about any one of several axes substantially parallel to the plane of the body part of the door and also in a plane substantially normal to the plane of the body part of the door.
